DESIGN FOR A MEAT SAW

David A. Meeker, Gerald B. Fox, and Burton E. Sullenberger, Troy, Ohio, assignors to The Hobart Manufacturing Company, Troy, Ohio, a corporation of Ohio

Application February 20, 1946, Serial No. 126,756

Term of patent 14 years

(Cl. D55—1)

To all whom it may concern:

Be it known that we, David A. Meeker, Gerald B. Fox and Burton E. Sullenberger, citizens of the United States of America, residing at Troy, in the county of Miami, State of Ohio, have invented a new, original, and ornamental Design for Meat Saw, of which the following is a specification, reference being had to the accompanying drawings, forming a part thereof, and in which

Fig. 1 is a side elevational view of a meat saw embodying our new design;

Fig. 2 is a front elevational view thereof; and

Fig. 3 is a view in perspective showing the front and other side of the same.

The design for the meat saw as shown is characterized by having generally smooth and plane outer surfaces which are substantially open and exposed and which have smoothly rounded corners.

We claim:

The ornamental design for a meat saw, substantially as shown and described.

DAVID A. MEEKER.

GERALD B. FOX.

BURTON E. SULLENBERGER.
